C. BAILDON.

UPHOLSTERY FABRIC.

No. 15,314.

Patented Aug. 26, 1884.

UNITED STATES PATENT OFFICE.

CHARLES BAILDON, OF PHILADELPHIA, PENNSYLVANIA, ASSIGNOR TO NOAH BARLOW, OF SAME PLACE.

DESIGN FOR AN UPHOLSTERY FABRIC.

SPECIFICATION forming part of Design No. 35,314, dated August 26, 1884.

Application filed July 10, 1884. Term of patent 3 years.

To all whom it may concern:

Be it known that I, CHARLES BAILDON, a subject of the Queen of Great Britain, residing at Philadelphia, in the county of Philadelphia and State of Pennsylvania, have invented and produced a new and original Design for Upholstery Tapestry or Damask, in such shades as may be desired; and I do hereby declare that the photographic print accompanying this specification conveys to any one skilled in the art a clear understanding of the same, and is sufficient to enable such persons to use my invention.

What I claim as my invention, and desire to secure by Letters Patent, is—

The design for upholstery tapestry or damask, as shown in the photographic print accompanying this specification.

CHARLES BAILDON.
